UNITED STATES PATENT OFFICE.

ERNEST RENÉ BAER, OF PARIS, FRANCE.

BELT BUCKLE.

Application filed April 18, 1924. Serial No. 707,478.

To all whom it may concern:

Be it known that I, ERNEST RENÉ BAER, a citizen of the French Republic, residing at 25 Boulevard de Belleville, Paris (XI), France, have invented new and useful Improvements in Belt Buckles, of which the following is a specification.

This invention relates to belt-buckles and has for its object to provide an improved buckle which allows of tightening the belt exactly to the desired point, any tension exerted at the ends of the belt on each side of the buckle having for effect to render it still more impossible for the belt to slip.

The improved buckle is constituted by a flanged plate supporting a cross-pin or axis and a pallet or tongue-piece centrally pivoted on said axis, one of the ends of the pallet having a cross-bar for the attachment of the belt and the other end of the pallet having its edge pressed into engagement with the portion of the belt lying behind the plate of the buckle, by the tension exerted on the belt; preferably the flanged plate supports a second pin or axis in such relation to the pallet that the end of the belt folded around the cross-bar without stitching will be gripped between the pivotal axis and the belt.

This buckle is of remarkable simplicity, the number of separate parts necessary to its construction being reduced to three. The grip obtained is instantaneous, automatic and proportional to the tension supported by the belt. Naturally, the external surface of the plate can be ornamented, nickel plated and otherwise treated. The belt once fastened by means of this buckle cannot come undone of itself under the action of forces which act upon it, but it can nevertheless be removed without any difficulty by an exceedingly simple operation.

On the accompanying drawing which shows for example one form of construction for carrying out the invention,

Figure 1 is a view of the buckle in plan from beneath, the leather strap of the belt being shown in dot and dash lines.

Figure 2 is a longitudinal section of the belt with its buckle.

In the example of construction represented in the drawing, it will be seen that the buckle comprises a plate 1 having preferably a curved shape; the surface 1^a of this plate which will be seen when the belt is worn will be suitably ornamented. The two

edges 2 of the said plate 1 are turned down on the side of the inner surface 1^b.

These two downturned edges or flanges serve to support and conceal the device for securing the belt. This device is constituted by a member 3, preferably in the form of a pallet or tongue-piece which can oscillate around the axis 4 carried by the flanges 2. In a slot 5 in this pallet there is engaged one of the ends 6^a of the strap 6, made of leather, fabric or other suitable material; this end is folded over and can be stitched by sewing at 7, but this is not necessary because the extremity 6^a passes first between the guide-pin 8 and the plate 1, then around one end of the pallet into the slot 5, and lastly beneath the axis 4, so that it finds itself gripped very firmly.

The passage of the strap beneath the axis 8 ensures for the end 6^a a position such that when a pull is exerted upon it the pallet 3 will be compelled to tilt around its axis 4; the edge 3^a of the pallet 3 then comes into contact with the inner surface 1^b of the plate 1, or with the inner face of the belt if this has been inserted through the buckle.

The working of the buckle is as follows:— The extremity 6^a of the belt being fixed to the member 3 as has been stated, the other end 6^b is engaged between the inner face 1^b of the plate 1 and the edge 3^a of the tongue-piece 3. By pulling the end 6^b in the direction of the arrow 9, the belt will be tightened. When the belt has been tightened, the extremity 6^b is released, becoming free, and the force which then tends to slacken the belt acts upon the end 6^b in the direction of the arrow 10 and upon the extremity 6^a in the direction of the arrow 11. It is seen that these forces cause the member 3 to tilt in the direction of the arrow 12, and to press its edge 3^a towards the plate 1. The extremity 6^b of the strap is therefore gripped and the belt cannot come unfastened.

In order to remove the belt, it suffices simply to press lightly upon 6^a in the direction of the arrow 13. The pallet 3 will tilt around the axis 4 in the direction opposite the arrow 12, thus separating the edge 3^a from the face 1^b of the buckle and thereby allowing the belt to slip in the direction of the arrow 10.

There can naturally be applied to the buckle as described suitable constructional modifications of detail without departing thereby from the scope of the invention.

Having thus described my invention what I claim is:—

A belt-buckle, comprising a plate, flanges at opposite sides of said plate, a pin extending between said flanges, a pallet pivotally mounted upon said pin, a second pin extending between said flanges, one end of said pallet projecting towards said plate, and a cross-

bar at the opposite end of said pallet, one extremity of the belt being attached to said pallet by passing between said pins and around said cross-bar. 10

In testimony whereof I have signed my name to this specification.

ERNEST RENÉ BAER.
